UNITED STATES PATENT OFFICE.

ORLANDO P. HARGROVE, OF WAYLAND, NEW YORK.

BUMPER FOR LOOMS AND THE LIKE.

1,383,940.

Specification of Letters Patent.

Patented July 5, 1921.

Application filed June 15, 1920. Serial No. 389,060.

To all whom it may concern:

Be it known that I, ORLANDO P. HARGROVE, a citizen of the United States, residing at Wayland, in the county of Steuben 5 and State of New York, have invented a new and useful Improvement in Bumpers for Looms and the like, of which the following is a specification.

This invention relates to bumpers of the kind with which the picking stick of a loom is adapted to coöperate to stop the movement of the picking stick after the shuttle has been sent across the loom.

Bumpers of this kind as heretofore made frequently consist of a body or block of resilient material secured to the frame of the loom, and these bumpers are objectionable because they do not possess sufficient resiliency and consequently cause frequent breaking of the picking stick. Other bumpers consist of a strip of leather or the like stretched across a pair of rigid arms. These bumpers were objectionable for the reason that the leather strips and the arms to which they are secured frequently break due to the continual shocks to which they were subjected to and to the fact that these bumpers do not possess sufficient resiliency.

The objects of this invention are to provide a bumper of this kind which will offer a gradually increasing resistance to the movement of the picking stick in such a manner as to materially reduce the tendency of the picking sticks to break and greatly increase the durability of the bumper; also to improve the construction of bumpers of this kind in other respects hereinafter specified.

In the accompanying drawings:

Fig. 1 is an elevation showing a bumper embodying the invention in operative relation to a part of the frame of a loom, and a picking stick.

Fig. 2 is a side elevation of the bumper on an enlarged scale.

Fig. 3 is a front elevation thereof.

Fig. 4 is a top plan view thereof.

Fig. 5 is a section thereof on line 5—5,

Fig. 4, on a reduced scale.

Referring to Fig. 1, A represents a part

of the frame of a loom and B the picking stick which is pivoted at its lower end and the upper end of which is adapted to strike the shuttle to pass the same across the loom. C represents in general a bumper or buffer 55 embodying this invention secured to the frame of the loom and adapted to stop the movement of the picking stick.

The bumper shown more in detail in Figs. 2 to 5 includes a frame member D which 60 may be of any suitable or desired construction and which in the construction shown has an intermediate flat portion d adapted to be secured to the frame of the loom, and end portions d' which extend outwardly 65 from the portion d. The frame D in the construction shown is made of a strip of metal having the end portions d' bent outwardly and twisted through a quarter of a revolution so that the ends thereof lie substantially in horizontal planes. A frame of any other suitable construction may be used if desired.

The picking stick is adapted to strike against a strap or band E which may be 75 made of leather or any other suitable flexible material and which is yieldingly stretched across the space between the outwardly projecting ends of the frame member in such a manner as to offer a gradually increasing 80 resistance to the movement of the picking stick after the stick strikes the intermediate portion of the strap. Any suitable means may be provided for holding the strap taut between the ends of the bumper frame and 85 for permitting the strap to yield. In the construction shown for this purpose the ends of the strap or band E pass around the outer portions of pulleys or rollers F arranged on the projecting ends of the bumper frame. 90 Any suitable means may be provided for stretching the strap tightly across the space between the two pulleys and for yieldingly resisting the movement of the strap out of this taut position by the picking stick. In 95 the construction shown for this purpose the ends of the strap E are connected by resiliency means which tend to hold the front portion or outer run of the strap or band E taut, and for this purpose a spring G is 100

used which is suitably connected with the ends of the strap or band E. The spring in the construction shown is provided at opposite ends with loops or eyes g through which rods g' extend. These rods are suitably connected to the ends of the strap by means of lacing g². Any other suitable means for connecting the ends of the spring with the ends of the strap E may, however, be used. When the picking stick strikes the middle portion of the strap or band E, this strap will be pushed inwardly by the force of the picking stick, as indicated in dotted lines in Fig. 4, thus stretching the spring G and turning the rollers or pulleys F slightly about their pivots. The strap or band E offers a gradually increasing resistance tending to check the movement of the picking stick, this resistance increasing as the strap is moved from its straight line position and as the stretch of the spring is increased.

In order to hold the strap E in the proper relation with reference to the pulleys or rollers F, the strap is preferably secured to each of the pulleys by any suitable means, such for example as a screw or pin e, Figs. 2 and 5 and the strap is also preferably held from moving downwardly out of engagement with the pulleys by means of flanges e' 30 extending outwardly from the lower portion of the pulleys.

By means of this arrangement the buffer offers a gradually increasing resistance to the movement of the picking stick and stops the picking stick gradually. The strap E not being rigidly secured at its ends yields by stretching the spring G and turns the pulleys F so that in case the picking stick strikes the buffer an exceptionally heavy blow, no damage results, and the blow is taken up by the stretching of the spring G. The buffer described, therefore, saves breakage of the leather straps heretofore used in place of the strap E and also saves breakage of the picking sticks. The buffer frame made as described also has the advantage of great strength due to the fact that the ends of the arms d' are bent to lie in the plane in which the pull of the strap E acts, so that the tendency to break these arms is greatly reduced. Due to the construction described, the arms d' are however not subjected to such severe shocks as would be the case if the strap were rigidly secured to the frame. The buffer also has the advantage that when it is desired to renew the strap, this can easily be done by detaching the spring from the ends of the strap and disconnecting the strap from the pulleys, and securing another strap to the spring and pulleys. If desired the connection between the strap and the pulleys may be omitted. The pulleys or rollers F may be pivotally mounted on the arms d' of the bumper frame

by any suitable means, for example, the 65 rollers may be pivoted on pins f, the lower ends of which are rigidly secured to the arms d' by means of nuts f' or the like.

In the operation of the device, the picking stick strikes the strap substantially midway between the pulleys and encounters comparatively little resistance in moving the strap out of the plane in which it is stretched. The resistance, however, increases very rapidly due to the action of the 75 spring and to the fact that the resistance offered to the movement of the picking stick increases rapidly as the strap is moved out of its normal position due to the direction in which the forces act. 80

I claim as my invention:

1. The combination with the frame of a loom and a picking stick, of a bumper for said picking stick including a frame member adapted to be secured to said loom frame and having arms extending outwardly from the loom frame, a flexible member adapted to be struck by said picking stick, parts on said arms across which said flexible member is stretched, and a spring connecting the 90 ends of said flexible member for stretching said flexible member and extending transversely of said arms. 85

2. A picking stick bumper for looms and the like, including a frame member having a body portion adapted to be secured to the loom frame and having arms extending outwardly beyond said body portion, a flexible member stretched between said arms and adapted to receive the blows of the picking 100 stick, and resilient means also arranged between said arms and connecting with the ends of said flexible member for stretching said flexible member across said arms. 95

3. A bumper for looms and the like, including a frame having a pair of outwardly extending arms, a pair of rollers pivoted on said arms and spaced apart, a band of flexible material extending across the space between said rollers and extending partly 110 around the same, and resilient means also extending across the space between said rollers and connecting the ends of said band for stretching the same across said space and resisting movement thereof. 115

4. A bumper for looms and the like, including a frame comprising a strip of metal provided with a rear portion having its flat faces arranged in substantially vertical planes and provided with arms which are 120 twisted to lie in substantially horizontal planes, a band of flexible material, and means for stretching said band across the space between said arms and for yieldingly resisting movement of said band. 125

5. A bumper for looms and the like, including a frame comprising a strip of metal provided with a rear portion having its

flat faces arranged in substantially vertical planes and provided with arms which are twisted to lie in substantially horizontal planes, rollers pivotally mounted on said 5 arms and adapted to turn about substantially vertical axes, a band of flexible material extending partly around said rollers and across the space between said rollers,

and means for resiliently opposing the movement of said band. ¹⁰
Witness my hand this 11th day of June, 1920.
